UNITED STATES PATENT OFFICE.

ALBERT G. WELCH AND ARNOLD A. WEIGEL, OF CHICAGO, ILLINOIS, ASSIGNEES, BY
MESNE ASSIGNMENTS, TO SOPHIE L. WOODS, OF CHICAGO, ILLINOIS.

ANTIFRICTION-BEARING.

1,316,124.

Specification of Letters Patent. Patented Sept. 16, 1919.

Application filed February 16, 1916. Serial No. 78,588.

To all whom it may concern:

Be it known that we, ALBERT G. WELCH and ARNOLD A. WEIGEL, citizens of the United States, and residents of Chicago, in 5 the county of Cook and State of Illinois, have invented certain new and useful Improvements in Antifriction-Bearings; and we do hereby declare that the following is a full, clear, and exact description thereof, 10 reference being had to the accompanying drawings, and to the letters of reference marked thereon, which form a part of this specification.

This invention relates to improvements in 15 antifriction bearings and is more particularly applicable to side bearings for railway cars. The invention consists of the matters hereinafter described and more particularly pointed out in the appended 20 claims.

The object of the invention is to provide 25 an antifriction bearing which will automatically adjust itself to the shifting positions of the parts between which it is interposed, as for instance the body and truck 30 bolsters of a railway car, so that the transmitted load is at all times distributed equally to the antifriction element in the direction of its rotative axis. The improved bearing thus provides for the relative rocking or swaying movement of the bolsters in 35 their vertical plane and eliminates the unequal wear of said element.

Other objects and advantages will appear 40 as we proceed with our specification.

In the drawings:

Figure 1 is a view partly in side elevation 45 and partly in longitudinal section of an antifriction bearing made in accordance 50 with our invention.

Fig. 2 is a top plan view of our improved 55 antifriction bearing, with a part of the casing shown as broken away to more clearly show the interior construction thereof.

Fig. 3 is a view in end elevation thereof.

Fig. 4 is a transverse sectional view 60 through our improved antifriction bearing, the plane of the section being indicated by the line 4—4 of Fig. 1.

Fig. 5 is a view in perspective of the 65 casing forming a part of our improved bearing, a part of said casing being illustrated as broken away to more clearly illustrate the interior construction thereof.

Fig. 6 is a view in perspective of the 55 rocking member or shoe, located within the casing and upon which the antifriction elements are adapted to travel.

Referring now to that embodiment of our 60 invention illustrated in the accompanying drawings: 10 indicates a casing which 65 encloses the antifriction bearing and 11—11 indicate the antifriction elements contained therein. The antifriction elements are in the form of rollers which are adapted to travel 70 in a longitudinal path in said casing. As herein illustrated the antifriction bearing is attached to the truck bolster of a railway 75 car. 13 indicates the said truck bolster and 14 indicates the associated body bolster 80 with which the bearing is adapted to be engaged.

The casing 10 is preferably of rectangular, elongated form and is open at its top and bottom. It comprises upright side and 85 end walls 15 and 16 respectively and made integral with the side walls are laterally projecting ears 10^a—10^a by means of which the casing is attached to the truck bolster 13. Intermediate its ends said casing is 90 provided with a transverse web 17, which braces the casing 10 at this place and divides it into two compartments. In each compartment is located one of the antifriction elements or rollers 11 which is adapted 95 for a limited longitudinal travel in its compartment. Each side and end wall is provided at its top edge with an inwardly extending flange 15^a—16^a respectively, which together with the transverse wall 17, define 90 openings 18 in the top of the casing through which the periphery of said rollers project. The said side wall flanges 15^a act also to prevent vertical displacement of the antifriction elements 11 as will presently appear.

Within the bottom of the casing 10 and bearing upon the truck bolster 13, is a rocker or shoe 20 which substantially closes the open bottom of the casing. Said rocker 100 or shoe is capable of a limited rocking movement transversely of the casing, that is transversely of the path of travel of the antifriction elements.

The rocker 20 is made in the form of an 105 open comparatively shallow casing having a horizontal bottom wall 21, upright end walls 22 and upright side walls 23 which

are made thicker than said end walls. The bottom surface 21^a of said bottom wall 21 is curved or rounded transversely for a purpose soon to appear. The side walls 23 5 are depressed below the end walls 22, throughout the greater part of their length and are curved upwardly approaching said end walls as indicated at 24. To the top edge of each side wall 22 is fixed a wear 10 plate 25 which is curved upwardly at its ends to fit the curved ends of said side walls.

Each antifriction element 11 is in the form of an intermediate roller body 11^a with reduced end bearing extensions 11^b. The 15 elements are thus generally of the familiar form of a roller with trunnions fixed at its ends, but the trunnions which constitute the bearing extensions 11^b are preferably of greater diameter relative to the diameter of 20 the body of the roller than is usual. The said bearing extensions, or trunnions, engage and are adapted to roll upon the wear plates or rails 25 at the sides of the shoe 20 and transmit the load through said shoe to the 25 truck bolster. The body 11^a of the antifriction element, on the other hand, projects through the slots 18 defined by the flanges 15^a at the top of the casing, as has been pointed out, and receives the load from the 30 body bolster.

At each end of the rocker or shoe 20 are fixed lugs 26—26 which engage within downwardly facing U-shaped bosses 27 formed integral (as shown) with the end 35 walls 16 of the casing 10. Said lugs 26 and bosses 27 have registering apertures 28 through which a cotter pin may be inserted to hold said casing and rocker together in shipment.

40 On the inner face of each side wall 15 of the casing in the vicinity of the transverse partition wall 17 are formed bosses 29—29 which extend into the vertical plane of the upright side walls of the rocker. The bottom 45 edge of each boss terminates a short distance below the bottom edge of said transverse wall 17 and during the rocking movement of said rocker or shoe, said bottom edges of said bosses are adapted to be engaged by and assist in limiting the transverse rocking movement of said rocker upon its associated bearing surface formed by the 50 top surface of the truck bolster.

The lateral upright faces 29^a of said bosses 55 29 are curved downwardly and outwardly near their bottom ends to form shoulders which coact with the upturned ends of the wear plates 25 to be engaged by the trunnions 11^b of the antifriction elements 11 to 60 limit the longitudinal movement of said elements in said casings. When said trunnions are in engagement with said shoulders and upturned ends of the wear plate 25 respectively, they will act as bearings against 65 which the antifriction elements may rotate

about an immovable axis, thus allowing for a greater amplitude of swinging movement between the body and truck bolsters.

When said antifriction elements are in the proper position in the casing with their 70 trunnions 11^b engaging and having rolling bearing upon the bearing rails or plates 25, the top of the roller body 11^a projects above the casing so as to be engaged by the body bolster 14 but the bottom of said body is 75 above the top surface of bottom wall 21 of said rocker and is thus free.

In the antifriction bearing herein before described the load is transmitted from the body bolster to the bodies 11^a of the antifriction elements and thence through the trunnions or bearing extensions 11^b to the side rails of the rocker 20, which rests and is adapted to rock upon the top of the body bolster. 85

It is apparent that when the load transmitted is greater at the ends of said antifriction elements 11 at one side of the casing than at the other, the rocker will rock transversely of the casing and the antifriction elements will be automatically brought to a 90 position to present the full intended contact.

Our improved antifriction bearing comprises but few parts which may be cheaply and economically constructed of the required strength to stand the strain imposed upon them. The arrangements of the parts are as such that a greater amplitude of swinging movement of the body bolster relative to the truck bolster is accommodated 100 for by the provision of two peripherical bearing surfaces of different diameters. This construction allows for the use of two independent traveling antifriction elements in a comparatively short casing as the distance through which said elements move in 105 said casing is materially reduced by the provision of such bearing surfaces.

While in describing our invention we have referred to certain details of mechanical 110 construction and arrangement of parts, we do not wish to be limited thereto except as may be pointed out in the appended claims.

We claim as our invention:

1. An antifriction bearing comprising in 115 combination with a support providing a bearing surface, a rocker having a bearing surface of an area approximately equaling its plan area, said rocker bearing surface being adapted to engage the bearing surface on said support, one of said bearing surfaces being a curved surface, an antifriction bearing having rolling bearing on 120 said rocker and movable in the direction of the axis of the rocking movement thereof and means for retaining said antifriction element in operative relation with said rocker. 125

2. An antifriction bearing comprising in 130 combination with a support providing a

bearing surface, a rocker having a bearing surface of an area approximately equaling its plan area, said rocker bearing surface being adapted to engage the bearing surface 5 on said support, one of said bearing surfaces being a curved surface, said rocker having spaced rails extending parallel to its axis of rocking movement, an antifriction element having trunnions which have rolling 10 bearing on said rails and means for retaining said antifriction element in operative relation with said rocker.

3. An antifriction bearing comprising a casing, a rocker in said casing, said rocker having a curved bearing surface on which it is adapted for a rocking movement transversely of said casing and an antifriction element longitudinally movable in said casing and having a rolling bearing on said 20 rocker.

4. An antifriction bearing comprising a casing, a rocker in said casing, having a transversely curved bearing surface of an area approximately equaling the plan area 25 of said rocker, an antifriction element adapted for a rolling bearing on the opposite side of said rocker and means limiting the rolling movement of said antifriction element.

5. An antifriction bearing comprising a 30 casing, a rocker in said casing adapted for a rocking movement transversely of said casing, said rocker having longitudinally extending spaced bearing rails, an antifriction element comprising a roller having trunnions, said roller being adapted to receive 35 the load and to transmit it through said trunnions, which have rolling bearing on said spaced bearing rails, said casing having means for retaining said antifriction 40 element in proper relation within the casing.

6. An antifriction bearing comprising a casing, a rocker in said casing adapted for a rocking movement transversely of said casing, said rocker having longitudinally extending spaced bearing rails, an antifriction element comprising a roller having trunnions, said roller being adapted to receive 45 the load and to transmit it through said trunnions, which have rolling bearing on 50 said spaced rails, said casing having means for retaining said antifriction element in proper relation within the casing and means limiting the longitudinal movement of said antifriction element in said casing.

55 7. An antifriction bearing comprising a casing open top and bottom, a rocker in said casing, said rocker having a transversely curved bottom bearing surface upon which it is adapted to rock in said casing, and having longitudinally extending spaced bearing rails on its top side, an antifriction element having bearing trunnions carried on 60 the rails of said rocker, said casing having means preventing vertical displacement of 65 said antifriction element and means on said

casing for limiting the rocking movement of said rocker in said casing.

8. An antifriction bearing comprising in combination with a support, a casing open top and bottom, fixed to said support, said 70 support providing a bearing surface defined by said casing, a rocker located within said casing adapted to rock on said bearing surface of said support transversely of said casing, said rocker having longitudinally extending upwardly facing bearing rails an 75 antifriction element having bearing trunnions which are adapted for rolling bearing on said upwardly facing bearing rails of said rocker, said casing having means for 80 preventing vertical displacement of said antifriction element.

9. An antifriction bearing comprising in combination with a support, a casing open top and bottom, fixed to said support, said 85 support providing an upwardly facing bearing surface defined by said casing, a rocker in said casing, said rocker having a transversely rounded bottom bearing surface adapted for engagement on the upwardly 90 facing bearing surface of said support, and longitudinally extending upwardly facing spaced bearing rails, a plurality of antifriction elements carried by said rocker, said 95 elements each having trunnions adapted for rolling bearing on said upwardly facing bearing rails of said rocker, said casing having means and said rocker having means at the ends of said upwardly facing bearing 100 surfaces limiting the rolling bearing of said trunnions on said rails.

10. An antifriction bearing comprising in combination with a support providing an upwardly facing bearing surface, a casing open top and bottom, fixed to said support, 105 said casing having means dividing it into two compartments, a rocker in said casing, said rocker having longitudinally spaced rails on its top side and a transversely rounded bottom bearing surface adapted for 110 engagement on said upwardly facing bearing surface of said support, an antifriction element located in each compartment of said casing, each of said elements having trunnions adapted for rolling bearing on said 115 spaced rails of said rocker, and said rocker having means and said casing having means limiting the rolling movement of said antifriction elements on said spaced rails of 120 said rocker.

11. In an antifriction bearing, a rocker therefor, said rocker having a transversely rounded bottom bearing surface and longitudinally extending upwardly facing spaced bearing rails on its top surface said bearing 125 rails terminating in upwardly curved portions at their ends.

12. In a side bearing for railway cars, a bearing plate, a roller to engage said plate, a cradle having side members which embrace 130

said roller and support the same, a member upon which the cradle is seated, and a saddle secured to said member and adapted for engagement with said cradle to hold it to its seat.

13. In a side bearing for railway cars, a bearing plate, a roller to engage said plate, a cradle having side members to embrace and support said roller, a member upon which the cradle is seated, and a saddle secured to said member and holding said cradle to its seat.

14. In a side bearing for railway cars, a bolster having a bearing surface, an opposed bolster, a saddle secured thereto, a cradle

having side members, and a roller supported by and between said side members, the saddle being adapted for engagement with said cradle to hold it to its seat upon said opposed bolster but permitting an oscillating movement between the saddle and the cradle. 20

In testimony, that we claim the foregoing as our invention we affix our signatures in the presence of two witnesses, this 3rd day of February A. D., 1916.
